(57) **CLAIM**

The ornamental design for a backpack with a side pouch, as shown and described.

DESCRIPTION

FIG. 1 is an isometric view of a backpack with a side pouch in accordance with this new design;

FIG. 2 is a rear elevation view of the apparatus of FIG. 1;
FIG. 3 is a front elevation view of the apparatus of FIG. 1;
FIG. 4 is a right side elevation view of the apparatus of FIG. 1;

FIG. 5 is a left side elevation view of the apparatus of FIG. 1;
FIG. 6 is an upper plan view of the apparatus of FIG. 1; and,
FIG. 7 is a lower plan view of the apparatus of FIG. 1.
The broken lines showing the backpack are for the purposes of illustrating environment and form no part of the claimed design.
